UNITED STATES PATENT OFFICE.

WARN GEORGE GEE, OF KANSAS CITY, MISSOURI, ASSIGNOR OF ONE-HALF TO W. A. SNAPP, OF DUNLAP, MISSOURI.

INSULATOR.

1,177,315.

Specification of Letters Patent.

Patented Mar. 28, 1916.

Application filed September 29, 1914. Serial No. 864,074.

To all whom it may concern:

Be it known that I, WARN G. GEE, a citizen of the United States, and a resident of Kansas City, county of Jackson, and State 5 of Missouri, have invented a new and Improved Insulator, of which the following is a full, clear, and exact description.

My invention relates to insulators to be formed of glass, or other non-conducting 10 material, and having means for securing the same on a pin or other support, and for engaging conductor wires.

The invention relates more particularly to 15 an insulator in which pairs of retaining lugs are provided on the insulator for engaging the wires.

The prime object of the invention is to 20 provide improved means for retaining a plurality of conductor wires, and whereby the engagement and disengagement of the wires are facilitated.

The invention will be particularly explained in the specific description following.

25 Reference is had to the accompanying drawings forming part of this specification, in which similar characters of reference indicate corresponding parts in all the views, and in which:

30 Figure 1 is a side elevation of an insulator formed in accordance with my invention; Fig. 2 is a vertical section on the line 2—2 Fig. 1; Fig. 3 is a horizontal section on the line 3—3 Fig. 2; Fig. 4 is a side elevation 35 showing a pair of the insulators in use.

In forming an insulator in accordance with my invention, the body 10 may be produced in glass, or other non-conducting material, and of the same general shape as insulators of this type. Suitable means, such 40 as the socket 11, is provided to fasten the insulator on a vertical pin or other support A.

I produce on the exterior of the insulator 45 between the upper and lower ends thereof, and preferably nearer to the upper end, a depressed zone 12, which may extend completely around the body 10. The depressed portion has a broad portion 13 to provide sufficient area adjacent to the conductor engaging elements. At the broad depressed area 13 I produce on the insulator pairs of lugs 14 and 15. The lugs of a pair are 50 spaced annularly, preferably about ninety degrees, and the lugs of one pair extend oppositely to the adjacent lugs of the opposite

pair. Each lug terminates in a lateral arm 16, the arms of a pair being in approximately the same plane, and the respective arms being disposed in planes transverse to the longitudinal axis of the body 10. The terminal 60 arm of the lug of one pair is so spaced from the adjacent arm of the opposite pair, that a space 17 is provided leading to the broad depressed area 13. The said space 17 thus provides an opening for the entrance and removal of the wires, the opening being common to the adjacent arms. The one opening therefore suffices for the two wires B and C, of which one is engaged by the upper pair of lugs 14 and the other is engaged by the 70 lower pair of lugs 15. The widening of the depressed portion produces what may be termed shoulders 18 adjacent to each lug 14 and 15, as best seen in Figs. 1 and 4. By the described construction either wire B or C is 75 entered in the described openings 17 and given sufficient bend to engage the said wire behind the hook formation presented by the lateral arm 16, thereby disposing the wire 80 between the lugs and the adjacent shoulders 18 on the body.

Having thus described my invention, what I claim as new and desire to secure by Letters Patent, is:

1. An insulator body having means where- 85 bv to secure to it a support, the exterior of the body having a pair of retaining lugs to engage a conductor wire, the said lugs projecting toward each other, presenting ends directly opposite to each other and spaced 90 apart for the entrance and removal of a wire, there being a depression in the insulator behind the lugs and communicating with the space between the lugs, to receive 95 an inserted wire.

2. An insulator having pairs of lugs, the lugs of a pair being spaced annularly, and the lugs of one pair projecting toward the adjacent lugs of the opposite pair and spaced therefrom, the insulator body presenting a depression at the said pairs of lugs, and the spaces between the terminals of adjacent lugs leading to the said depression and affording a restricted entrance and outlet opening common to the respective opposite lugs.

3. An insulator comprising a body having pairs of lugs, the lugs of a pair being spaced annularly, and the lugs of one pair being disposed oppositely to the adjacent lugs of 110

the other pair, the several lugs being spaced from the lateral surface of the body to accommodate conductor wires, and the said opposite adjacent lugs being spaced and forming therebetween an opening common to the opposite lugs, for the entrance and removal of the conductor wires.

4. An insulator comprising a body having pairs of lugs, the lugs of a pair being spaced 10 annularly, and the lugs of one pair being disposed oppositely to the adjacent lugs of the other pair, the several lugs being spaced from the lateral surface of the body to accommodate conductor wires, and the said 15 opposite adjacent lugs being spaced and forming therebetween an opening common to the opposite lugs, for the entrance and removal of the conductor wires, the several lugs having lateral terminal arms lying in 20 planes transverse to the axis of the body, and the arms of a pair lying in the same plane.

Copies of this patent may be obtained for five cents each, by addressing the "Commissioner of Patents,
Washington, D. C."

5. An insulator body having means whereby to secure a support, the exterior of the body having a pair of retaining lugs to engage 25 a conductor wire, the lugs being directly opposite to each other, their terminals being spaced from each other, and the said body presenting a depression adjacent to the lugs to receive the wire, the body furthermore having shoulders annularly in line 30 with the lugs and spaced from the latter, the lugs being formed with lateral terminal arms disposed in opposite directions and in alinement in a plane transverse to the axis 35 of the insulator.

In testimony whereof I have signed my name to this specification in the presence of two subscribing witnesses.

WARN GEORGE GEE.
